Claims priority, application Italy June 15, 1955

3 Claims. (Cl. 139—77)

Some dobbies for looms at present in use are mounted on the looms in awkward positions, not only in regard to the obstruction caused and the weight, but also in regard to the difficulty of having access to the different members utilised to connect the loom with the healds.

The dobbies which will hereinafter be described is provided with improved operating means and is more conveniently arranged on the loom without any increase in the space occupied or in the height of the loom. Pulleys, cables, transmission shafts and other means for connection of the dobbies to the healds are eliminated, whereby there is obtained a better efficiency and elimination of play and friction common to other known constructions.

The improved dobbies can be disposed inside a loom of any type since the free space beneath the healds is always large and suffices for this purpose. This arrangement ensures greater facility for examining and dismantling the different constituent parts of the dobbies. The control of the clutch and de-clutching means for all the parts serving for the displacement of the blades is entirely mechanical and is ensured by means of steel wires mounted in appropriate sheaths joined in the form of a beam so as to terminate in a control casing or box arranged at the exterior and carrying the punched cards. All the driving means in the frame of the dobbies and in the control casing or box are in a flow of lubricating oil circulating under pressure by the action of a double action pump arranged at the interior of the frame.

An embodiment of dobbies in accordance with the invention is hereinafter particularly described with reference to the figures of the accompanying drawings, wherein:

Fig. 1 shows a transverse section of the dobbies.

Fig. 2 shows a longitudinal section of the latter.

Figs. 3 and 4 show details of the operating means for the healds, Fig. 3 being a view taken in the direction Y (Fig. 2) after removal of the cover 31, while Fig. 4 is a similar view but where the lever is in the working position.

Fig. 5 shows a section of the control casing or box with the cylinders and driving members for the cables which transmit the impulses to the clutch and de-clutching members of the sinkers.

Figs. 6 and 6a together form an assembled view of the dobbies and the driving casing or box mounted on the loom.

Fig. 7a shows a vertical central section of the cylinder having a scroll groove 7a.

Fig. 7b shows a corresponding elevation thereof.

Fig. 8a shows a front elevation, and Fig. 8b a side elevation of an assembly of oscillating bar and racks.

Fig. 9a shows an elevation, and Fig. 9b shows a section on the line A—A thereof, of an assembly of toothed sectors.

Fig. 10 is an elevation of an assembly wherein a rocker arm is coupled to cranks.

Fig. 11a is a side elevation, and Fig. 11b is an edge elevation, of a slide.

The position of the frame of the dobbies is unalterable whereas that of the control casing or box can vary, the

two entities being connected at a distance by means of flexible cables.

Referring to Fig. 2, 1 designates a disc cam mounted on one end of a cylinder on a shaft 37 connected to a central drive shaft 36 by a chain 34 and sprockets, as shown in Fig. 6, with a ratio of 1:1. A disc cam 1 is mounted on each end of the cylinder, in the periphery of which is hollowed out a cam groove or scroll 7a which, by means of a cam follower 3 connected to a toothed sector 2 imparts a rocking motion to the latter. The motion includes two stationary periods. As can be seen from Figures 7a and 7b, cam groove 7a is made so as to have, at each half turn, a straight stretch extending over 65°. Consequently, along such stretch of 65° the cam follower is not subject to any displacement.

The teeth of the sector 2 are engaged with the racks 4, carrying the bars 5, moving with a to and fro motion in a vertical plane along the guiding means 6. In each of the groove elements in the two end faces of the cylinder is engaged a cam follower roller 8 carried by a bell crank lever 9.

The two levers 9 are coupled to the two stop rods 10 (see Figures 1 and 2). The motion of the said levers 9 coincides exactly with the period of 65° referred to above, that is to say when all the dobbies members are stationary for a certain period of time. This happens precisely at each half turn because the two cams 7, as shown in Figure 7, have their respective pivoted members displaced by 180° in relation to each other, and consequently the two stop rods 10 move alternately at each half turn of the cylinder. Thus, at each rotation of the cylinder cam 1, there are obtained two stoppages of movement in opposite directions of the toothed sector, during which the bell crank lever 9 executes a similar to and fro movement causing lowering and raising of the rods 10 the purpose of which is to lock and unlock respectively the pivoted members 11 which oscillate on the shaft 12.

Sinkers 13 are pivotably mounted in slides 14, as shown in the Figures 10 and 11, and can assume only two positions, namely a position of engagement with the bar 5 (see Figure 10 and left hand side of Figure 1), and a position of disengagement from the bar 5 and of engagement with the pivoted member 11 (see right hand side of Figure 1). The slides 14 have notches 15 in which engage the rollers 16 carried by the rocker arm 17, Fig. 1. On the axis of this rocker arm are pivotally mounted the connecting rods 18 subjected to the action of the blades or cranks 19 at the opposite ends of which are secured the rods 20 connected with the healds 21 as shown at Fig. 6. The shaft about which the cranks 19 rotate consists of two halves a and b held together by the rings c. Such a construction permits an easy return of the healds to the zero position as will be hereinafter described in greater detail.

The control cables 23 disposed in sheaths (Fig. 5) start from the control casing or box where they are coupled to hooks 24 kept in engagement selectively with one or other of two knives 25 by deflectors 27 operating in accordance with the actuation of the needles 26. The knives 25 move simultaneously in guiding slots 30 and they reciprocate vertically in relation to each other in a predetermined manner during the working period under the action of a cam driven by the transmission shaft 37. The feeler needles 26 are raised and lowered in a predetermined manner by the crank 28 at each rotation of the driving shaft 36 and they are maintained in their upper or high position during the whole of the time in which the cylinder 22 carrying the punched cards advances them by one step. If, during the following descent, the feeler needles 26 come opposite a hole in the punched card the punch rod 29 displaces that de-

ffector 27 which is coupled to the hook 24 engaged with the uppermost knife 25, which thus has to carry it up and pull also the cable 23. At the same moment, the rod 10 (Fig. 1) is lowered by reason of the fact that it is actuated, as indicated, by the cranked lever 9, in such a manner as to unlock the pivoted member 11 which, under the action of the cable 23, will be moved and will push back the hook of the sinker 13 beneath the bar 5. The latter, in its ultimate descent, will carry along the slide 14 as well as the rocker arm 17 towards the bottom. Through the intermediary of the connecting rods 18 and cranks 19, this produces lifting of the healds. In working position, the pivoted member 11 ensures the engagement or hooking of the slide 14 onto the bar 5 and in its upward return stroke this latter brings back the slide 14 to its initial position. The to and fro movement continues so long as the sinker 13 remains hooked to the bar 5, that is to say so long as the feeler needle 26 has in front of it a hole in the punched card. When the feeler needle 26 (see Fig. 5) remains uplifted because there is no perforation in front of it, the deflector 27 which is no longer displaced by the punch 29, brings back the hook 24 into engagement with the lower knife 25 which causes the hook 24 to descend and push back, during the said descent, the cable 23 and thereby also the pivoted member 11 (see Fig. 1). This member, unlocked at this moment in relation to the bar 10, brings the sinker 13 to its position of rest and the healds remain stationary in their lower positions. When the healds have to remain stationary in their upper position, the two corresponding needles 26 will be lowered and produce successively the engagement of the sinkers 13 on the right and on the left; the right hand bar 5 descends and carries along with it the slide 14 which causes the raising of the healds. On the other hand, the left hand bar rises and, having arrived at its upper position, the left hand sinker 13 becomes hooked on. At this moment, while the rocker arm 17 rises at the right hand side, it descends at the left hand side so effecting an oscillatory movement keeping its axis stationary, the connecting rods 18 remaining in their vertical plane; in consequence the healds remain in their upper position until one of the feeler needles 26 remains raised because of the absence of any perforation in the punched card in front of it, the healds then again taking up their to and fro movement starting from the position at which they stopped.

There will now be described the adjustment or regulation of the healds. As will be seen in Figs. 1 and 3, the axis of the blades 19 comprises two bars *a* and *b*, secured by the ring *c*, and on the external periphery of which oscillate the blades proper (Fig. 1). The bars *a* and *b* are locked in their turn in the position indicated by the detents *d* and *f* which are capable of displacement in both directions along the two guides 35 of the frame. The racks carried by the detents *d* and *f* are engaged with the pinion *i* which itself meshes with the toothed sector *l* keyed on the shaft *m*. The arm *n* (Figs. 2 and 6) secured on the same shaft is coupled to a connecting rod carrying a lever capable of being actuated by hand from the exterior of the frame. A safety device prevents any risk of effecting adjustment of the healds during operation of the loom.

The detents *d* and *f* have at their ends two inclined surfaces *o* and *p* along which can move the small rollers *q* and *r*. The cranks *s* and *t* pivot at *u* and are connected to the slides *v* by an arm, the other arm of each crank being pivoted at *w* to a rod (not shown) which connects these cranks together. Fig. 4 shows the bars *a* and *b* in the more widely separated position, seen also in Fig. 1. The detents *d* and *f* lock the bars *a* and *b* when the rollers *q* and *r* ride along and up the inclined surfaces of the detents of the slides, into the position of maximum separation. To adjust the healds, the bars *a*

and *b* are brought together in such a manner as to eliminate the pivot about which the blades 19 turn.

This result is obtained by withdrawing the detents *d* and *f* by rotation of the toothed sector *l* and the pinion wheel *i*, by moving the arm *n*. The cranks *s* and *t* being connected with the detents *d* and *f* will then turn about *u* so raising the rod *w*. The latter, in rising, lifts the blades and the lower healds, the upper healds descending by their own weight until at half way they meet the rod *w*. At this moment, the bars *a* and *b* will be connected on all sides with the common axis in unlocking the ring *c* (see Fig. 1).

To return the healds to the original position, it is necessary to reverse the displacement of the arm *n* and to return the detents *d* and *f* to their working position. The inclined surfaces of the detents engaged between the rollers of the bars *a* and *b* which are thus moved apart, until they again lock the rings *c*; at the same time the rod *w* will be lowered and move the blades 19 apart.

I claim:

1. A loom dobby comprising a casing for disposal within the loom frame below the healds, two parallel horizontal spaced pivot shafts in said casing, a plurality of levers journaled on said shafts and arranged in pairs constituted by the adjacent levers on the two shafts, a plurality of healds, means coupling each pair of levers to a heald, pairs of spaced vertical guides in the casing positioned below each pair of levers, slide members in each guide, a plurality of rockers, corresponding in number to the healds, disposed in the casing and coupled to opposed slide members, means coupling each rocker by its centre to each lever of a pair, two spaced horizontal parallel drive bars vertically movable in the casing, means for driving said bars in out-of-phase reciprocation, and means for selectively coupling one and the other and both of the slide members to the associated vertically reciprocating drive bar, whereby when either of the slide members is coupled to its drive bar, the associated rocker is moved to lift the associated heald to a half-raised position, and when both the slide members are coupled to their drive bars, the associated rocker is moved to lift the associated heald to a fully raised position.

2. A loom dobby, as claimed in claim 1, wherein the means for driving the bars in out-of-phase reciprocation comprise a rotatable drive shaft journaled in the casing, a cylinder secured on said shaft and having a scroll cam groove in its cylindrical surface, a toothed sector journalled in the casing, a cam follower on said sector engaged in the cam groove of the cylinder, the groove being so shaped as to reciprocate the sector angularly, and opposed vertically movable racks meshed with said sector and coupled to the drive bars.

3. A loom dobby, as claimed in claim 1, wherein means for selectively coupling the slide members to the drive bars comprise catch means on the slide members operable to engage with the drive bars, control cables having an outer sheath coupled to the casing and to a control box and an inner longitudinally slidable wire coupled to the respective catch elements in the casing and to a control box and an inner longitudinally slidable wire coupled to the respective catch elements in the casing and to clutch elements in the control box, driven reciprocating slides in the control box, and punched card and feeler needle means in the control box serving to couple the clutch elements to the slides according to the pattern to be woven.
